UNITED STATES PATENT OFFICE.

WILLIAM HANSEN, HANS C. HANSEN, AND CHARLES BEARBY, OF CHICAGO, ILLINOIS.

SAFETY FENDER FOR AUTOMOBILES.

1,420,036.

Specification of Letters Patent. Patented June 20, 1922.

Application filed September 24, 1921. Serial No. 502,903.

To all whom it may concern:

Be it known that we, WILLIAM HANSEN, HANS C. HANSEN, and CHARLES BEARBY, citizens of the United States, and residents 5 of the city of Chicago, county of Cook, and State of Illinois, have invented certain new and useful Improvements in Safety Fenders for Automobiles, of which the following is a specification.

10 This invention relates to a safety fender for automobiles, and has for its object the provision of a fender disposed at the front of the automobile which is normally retained in folded or inoperative position but which 15 may be either manually tripped by the operator or automatically tripped by encountering an object so as to move to operative position to cushion the impact of the machine and to pick up the object struck.

20 Other objects will appear hereinafter.

The invention consists in the combinations and arrangements of parts hereinafter described and claimed.

25 The invention will be best understood by reference to the accompanying drawings forming a part of this specification, and in which,

Fig. 1 is a side elevation of the invention showing the device in inoperative position;

30 Fig. 2 is an enlarged sectional view on the line 2—2 of Fig. 7;

Fig. 3 is a view similar to Fig. 1 showing the invention in operative position;

Fig. 4 is a top plan view of the device 35 showing means for attaching same to the automobile;

Fig. 5 is an enlarged detail sectional view on the line 5—5 of Fig. 1;

40 Fig. 6 is a sectional view on the line 6—6 of Fig. 4;

Fig. 7 is a front elevation of the invention showing same in operative position;

Fig. 8 is a sectional view on the line 8—8 of Fig. 3; and

45 Fig. 9 is an enlarged sectional detail view on the line 9—9 of Fig. 7.

The invention comprises supporting arms 1 and 2 each having its inner end secured to the side frame of the automobile by any suitable means, but we preferably provide on the inner ends of said arms 1 and 2, looped brackets 3 and 4 through which are inserted hooks 5 each of said hooks having a shank 6 extending beneath the channel bar 7 of 50 the side frame of the automobile. Loosely mounted on the shank 6 of each of the hooks

5 is a slotted clamping member 8 which engages one side of the channel bar 7 and is held tightly in engagement therewith by means of a nut 9 threaded on the shank 6. 60 As many of such clamping hooks may be provided as desired. In practice one hook for each bracket is ordinarily sufficient to properly support the arms on the frame of the automobile. 65

The sets of levers attached to the arms 1 and 2 are identical in construction and operation and a description of one set of such levers will suffice to set forth the construction of the companion set of levers, and the same 70 reference numerals will be used to designate similar parts of both sets of levers. Pivotedly mounted on the arm 1 near the inner end thereof is a bar 10 said bar being provided with a loop 11 near its outer end, and 75 having a hook 12 mounted intermediate its ends for a purpose hereinafter described.

At the outer end of the arm 1 is pivotally mounted a swinging lever 13, the short end of which terminates in a hook or cam portion 80 14. A link 15 has one end pivoted to the short end of the lever 13 at the rear of the cam portion 14, its opposite end being slotted as at 16, and pivotally engaging a pin 17 provided on the bar 10, as clearly shown 85 in Figs. 1 and 2. A suitable spring 18 is mounted on the arm 1 near the rear end thereof and is adapted to bear against the bar 10 when the device is in closed position, and serves to forcibly urge the bar 10 away 90 from the arm 1 when the releasing mechanism is operated.

A leaf spring 19 is mounted on the link 15, the upper end of which provides a catch 20 having a cam surface which is engaged by 95 a lateral projection 21 on the hook 12 to raise the catch until same snaps over such projection thereby locking the levers in extended position.

The ends of the bars 10 are each bored 100 to receive a short sleeve 22 which is held in position by means of a set screw or any suitable means. The outer ends of the swinging levers 13 are likewise bored to accommodate similar short sleeves 23. 105 Loosely mounted in the sleeves 22, 23, and projecting beyond same a suitable distance on each side are lengths of tubing 24, to which canvas or other suitable material is secured by any suitable means, the canvas 110 being slotted adjacent the sleeves which provide bearings for tripping members mount-

ed thereon, as hereinafter described. The canvas preferably is mounted so as to bag slightly when the device is in operative position to lessen the shock when picking up the object struck by an automobile equipped with the device. Such shock is also greatly lessened by the play between the canvas carrying members mounted on the ends of the levers, afforded by the 10 sliding movement of the pins 17 in the slots 16. The canvas or other material is also provided with a resilient stiffening member 25 extending transversely thereof substantially between its upper and lower ends when in operative position, on which the canvas can be conveniently rolled as shown in Fig. 1, such roll resting in the loops 11 in the bars 10 provided for the purpose, when the device is in inoperative position. 15 Thus the canvas can be conveniently rolled up and carried when the device is in inoperative position and will smoothly and quickly unroll when the device assumes operative position.

20 25 Any suitable means may be employed for retaining the device in inoperative position, and for releasing said retaining means to permit the device to quickly assume operative position. We preferably employ a 30 tripping member automatically operable on encountering an object. Loosely mounted on the sleeves 22 are triggers 26 preferably of the type shown in Fig. 9 consisting of a hook 27 adapted to engage a sleeve 23, a stop 28 adapted to abut against an arm 10 to limit the pivotal movement of the trigger on the sleeve and an extension 29 having a bore in its end. Extending 35 through the tubing 24 carrying the lower end of the canvas is a rod 30 having threaded on its opposite ends fingers 31, each of such fingers having a bore in its outer end. Extending through the outer ends of the fingers 31 and the triggers 26 40 is a rod 32 such rod being held in position by means of set screws 33 mounted on the triggers 26. By this arrangement it will be seen that when the device is in 45 closed position the hooks 27 on the triggers 26 will engage the sleeves 23 and thus hold the device in inoperative position. On encountering an object a slight impact at any point along the length of the rod 32 will disengage the hooks 27 from the sleeves 23 50 allowing the apparatus to quickly assume its operative position. The stops 28 on the triggers 26 will prevent undesirable movement of the rod 32. A cable (not shown) may be attached to the rod 32 in order to 55 permit the operator of the machine to operate the triggers 26.

The device is normally in inoperative position, having canvas or other material rolled up as described on the resilient strip 60 65 25 so as to fit nicely in the loops 11 and

the hooks 27 are engaged with the sleeves 23 as above described. The device in inoperative position resembles an ordinary bumper and is neat and attractive in appearance. When an object is struck the 70 rod 32 projecting forwardly the greatest distance is moved backwardly and upwardly, thus disengaging the hooks 27 from the sleeves 23; or such hooks may be disengaged by means of a cable extending 75 to the operator's seat. With the hooks 27 disengaged, the bars 10 are forced downwardly by the springs 18 and by gravity and the levers 13 are swung upwardly by means of the link 15 until the catch on said 80 link engages the lateral projection on the hook 12 which locks the joint between such levers and holds same in extended position. The canvas mounted on the ends of the bars 10 and levers 13 in open position is slack 85 to cushion the force of impact of an object striking same and the slot 16 causes further slackening of the canvas due to the play permitted by said slot between the ends of the bars and levers.

90 The device is simple in construction, quick and positive in operation and can be manufactured economically.

95 While we have illustrated and described the preferred form of construction for carrying our invention into effect, this is capable of variation and modification without departing from the spirit of the invention. We, therefore, do not wish to be limited to the precise details of the construction set forth, but desire to avail ourselves of such variations and modifications as come within the scope of the appended 100 claims.

105 Having described our invention, what we claim as new and desire to secure by Letters Patent is:

1. An automobile fender comprising hinged frames; means operatively connecting said frames and forming a toggle; and latching means on said connecting means for automatically locking said toggle in extended position.

110 2. An automobile fender comprising hinged frames; means operatively connecting said frames and forming a toggle; and resilient means mounted on said connecting means for automatically locking said toggle in extended position.

115 3. An automobile fender comprising hinged frames; means operatively connecting said frames and forming a toggle; and resilient means mounted on said connecting means for automatically locking said toggle in extended position, said toggle means in 120 unlocked position serving as cam means for closing said frames.

125 4. An automobile fender comprising hinged frames; cushioning means mounted on said frames; means for locking said 130

- frames in extended position; and means for allowing play between the extended frames.
5. An automobile fender comprising a support; a bar pivotally mounted on said support; a lever pivotally mounted on said support and operable to extended position by said bar; and a slot in said lever slidably engaging the stud on said bar to permit play therebetween in extended position.
- 10 6. An automobile fender comprising hinged frames; means for holding said frames in closed position; resilient means for opening said frames; and means operatively connecting said frames forming a self-locking toggle.
- 20 7. An automobile fender comprising hinged frames; means for holding said frames in closed position; resilient means for opening said frames; a toggle operatively connecting said frames; and means for locking said toggle in extended position.
- 25 8. An automobile fender comprising a support; a bar pivotally mounted on said support; a lever pivotally mounted on said support and operable to extended position by said bar; and a toggle connection between said lever and said bar.
- 30 9. An automobile fender comprising a support; a bar pivotally mounted on said support; a lever pivotally mounted on said support and operable to extended position by said bar; and connecting means between said bar and lever to permit play therebetween in extended position.
- 35 10. An automobile fender comprising a support; a bar pivotally mounted on said support; a lever pivotally mounted on said support and operable to extended position by said bar; resilient means normally urging said bar and lever to operative position; a toggle connection between said bar and said lever; and means for permitting play between said bar and said lever in extended position.
- 40 11. An automobile fender comprising a support; a bar pivotally mounted on said support; a lever pivotally mounted on said support; and cam means mounted on said lever for raising said bar when said lever is operated.
- 45 12. An automobile fender comprising a support; a bar pivotally mounted on said support; a lever pivotally mounted on said support; a toggle connection between said bar and said lever; and means mounted on said lever for raising said bar when said lever is operated.
- 55 13. In an automobile fender comprising a bar and a lever; a projection on said lever; a link connecting said bar and said lever;
- and a catch engaging said projection to form a toggle.
14. In an automobile fender comprising a bar and a lever; a projection on said lever; a link connecting said bar and said lever; 65 and a spring latch to form a toggle and lock same in position.
15. An automobile fender comprising a bar and a lever; a cam portion on said lever; a link connecting said bar and said lever; 70 and a hook on said bar adapted to engage said cam portion to close said fender.
16. An automobile fender comprising hinged frames operatively connected together; triggers mounted on said frames 75 adapted to hold same in closed position; and means for tripping said triggers to extend said frames.
17. An automobile fender comprising hinged frames operatively connected together; triggers mounted on said frames 80 adapted to hold same in closed position; and means for automatically tripping said triggers.
18. An automobile fender comprising supports mounted on an angle bar constituting the side frame of an automobile; and hooks engaging said supports and having split clamping members for engaging said angle bar for holding said hooks in operative 85 position.
19. An automobile fender comprising hinged frames; depressions adjacent the ends of one of said frames; a cushion member having its opposite ends secured to said 90 frames; and a transverse rib secured intermediate the ends of said cushion member and adapted to have same rolled thereon and deposited in said depressions.
20. An automobile fender comprising 100 hinged frames; sleeves mounted in each of said frames; a rod extending through the sleeves of each of said frames; a cushion member having its opposite ends secured to said rods, triggers pivotally mounted on the 105 sleeves of one of said frames and adapted to retain same in closed relation; and a rod carried by said triggers and operable by impact thereagainst to trip said triggers and permit said frames to assume operative position. 110
